Application April 14, 1943, Serial No. 483,031

14 Claims. (Cl. 250—40)

1

This invention relates to antenna tuning apparatus and more particularly to antenna loading devices for securing maximum radiation of low frequency energy from aircraft antennas at high altitudes.

The antennas used by aircraft are limited in size by the requirements of aerodynamics and maneuverability so that when radio frequency energy at frequencies below 500 kilocycles per second is to be radiated, the antennas used are characterized by very high capacitive reactance. For maximum radiation of power, it is necessary that the high negative reactance of the antenna be cancelled by an equally high positive reactance (inductance) in the circuits between the output stage of the transmitter supplying the energy and the antenna. So long as transmitters were designed to work over only one frequency band, it was most convenient to provide all the necessary circuit elements within the transmitter housing, and when the frequency band over which the transmitter operated was sufficiently high to eliminate the need for the reactance neutralizing, or loading provisions as they are called, these were omitted with a consequent decrease in the size and weight of the transmitter.

Antenna loading circuits in which the amount of negative reactance to be neutralized is large are characterized by the appearance of very high voltage across the loading reactor and the antenna as is customary in resonant series circuits, and the presence of these voltages requires that the equipment be designed to provide very large clearance between all parts of the antenna circuit at high voltage to prevent corona and arc-over. When radiating modulated continuous waves with a power of 100 watts at 300 kilocycles, it is not unusual to find peak potentials of 20,000 volts at the terminals of the antenna and the loading inductor with some of the frequently employed types of antennas.

The large spacings to prevent corona and arc-over are necessary only at low frequencies, and it is obviously wasteful of space and material to make any such provisions in high frequency transmitters. Therefore, with the advent of multiple channel transmitters in which the individual channels may be set to operate at any frequency between 300 kilocycles and 10 megacycles per second, the antenna loading equipment was eliminated from the transmitter itself and made available in a separate unit, termed an antenna loading unit. With the equipment split up in this manner, it is possible for those individuals requiring only the use of high frequency channels

2

to install only the transmitter unit in the aircraft, eliminating the weight of the antenna loading unit which is superfluous for their purposes, while in installations in which low frequency operation is required, both the transmitter itself and the antenna loading unit are installed. The apparatus described herein is an improved antenna loading unit and is designed to be connected between the output of a radio transmitter and an antenna.

It is customary to control multiple channel transmitters remotely; that is, the operation of a remote control box located conveniently to the operator switches the transmitter, which may be located in an entirely different part of the aircraft, into operation on a preset channel frequency and the antenna loading units now in use are also adapted for remote control, automatically inserting a coil of preset inductance between the transmitter and antenna on the low frequency channels, a different coil for each channel, and connecting the transmitter output directly to the antenna on all the high frequency channels. In the antenna loading unit, it has been customary to use a different coil for operation on each low frequency channel with the various coils selected by means of a large rotary tap switch and the high voltages encountered have forced the use of very great spacing for the taps to prevent arc-over when operating under the low air pressures characteristic of very high altitudes. The resultant switch design has been large, bulky, fragile, and difficult to manufacture, and the large number of coils required to provide for operation on a number of channels has been such as to impart excessive weight and bulk to the antenna loading unit.

One of the principal objects of this invention is to provide an improved remotely controlled 40 multiple channel antenna loading unit of lesser bulk and weight than the equipment hitherto available.

Another object of the invention is to provide a new and novel remotely controlled multiple 45 channel antenna loading unit operating safely into antennas having high capacitive reactance at higher altitudes than possible with equipment previously available.

A further object of the invention is to provide 50 a new and novel remotely controlled multiple channel antenna loading unit in which unused elements do not absorb power from the transmitter output.

The above objects and advantages are accomplished by the use of three serially connected

55

variometers carried on a common rotatable shaft with taps brought out from each of the variometers, a vacuum relay alternatively connecting the transmitter output directly to the antenna and to the antenna in series with one or more of said variometers, and a cooperating sector and contact for disconnecting the variometer assembly from the antenna upon the rotation of the variometer shaft to a predetermined position.

Other objects and advantages of the invention will in part be disclosed and in part be obvious when the following specification is read in conjunction with the drawings in which:

Figure 1 is a right side view of the tuning unit with the case removed.

Figure 2 is a top view of the tuning unit variometer assembly removed from the apparatus.

Figure 3 is a sectional view of a variometer rotor.

Figure 4 is a front view of a slip ring and flexible drive coupling assembly.

Figure 5 is a side view of the slip ring and flexible drive coupling assembly.

Figure 6 is an end view of the variometer assembly showing the shaft operated disconnect mechanism.

Figure 7 is a schematic diagram of the electrical circuits utilized in the tuning unit.

In the drawings, like parts are designated by like reference characters.

Referring to Figure 1, the radio frequency input terminal 1 is connected to a terminal stud on the indicating meter 2 by the connecting lead 3. The meter 2 is mounted on the tuning unit front panel 4 and its two terminals are shunted by the coil 5, which insures continued energy transfer to the antenna circuits in the event of meter burnout. The inductance of coil 5 is such that 90% or more of the input current flows through meter 2. The other terminal stud of the meter 2 is connected by the lead 8 to the movable element of a single-pole-double-throw vacuum relay 6 actuated by the operating coil 7. In the de-energized position of relay 6, the lead 8 is connected to the rear relay contact and to the radio frequency output terminal 9 by the lead 10 provided with the anti-corona terminals 12 and 13. In the present design, a radius of one-half inch has been found very satisfactory on terminals 12 and 13. With the relay 6 in the energized position, the lead 8 is connected to the front contact of the relay, through the flexible lead 11 to the quick detachable connector 14 which may be attached to the contact 15 as shown, or alternatively connected to the contact 16 or 17. Contact 17 is provided with a corona shield 18 which remains in place at all times except when the connector 14 is attached thereto. The contacts 15, 16, 17 are carried on the variometer support rod 19 of insulating material such as that known to the trade as Bakelite, and the support rod 19 in turn is supported from the base of the unit by the stand-off support rods 20. A second variometer support rod 19 less the terminals 15, 16, 17 is similarly located on the other side of the tuning unit base and the two variometer support rods 19 between them support the three variometer assemblies 21, 22, 23. In Figure 1, only the fixed variometer coils may be seen. The rear winding terminal of the winding 24 is connected to the metallic series connector 27 bridging the gap between the structures of variometers 21 and 22, and the front winding terminal of the winding 25 is also connected to the metallic series connector

27, thus connecting the windings of these two variometers in series. The series connector 27 also serves to support the contact brush 28 engaging the slip ring 29 which is connected to the rear winding terminal of the variometer rotor winding of variometer 21 and to the front winding terminal of the variometer rotor winding of variometer 22. Brush 28 is in electrical contact with connector 27 and the connecting link 30 completes the connection between the connector 27 and the terminal 16 which is thus connected to the junction between the series connected variometers 21 and 22. The slip ring 29 is so constructed that it also serves as a flexible driving member as will be detailed in a later figure. The front winding terminal of the rotor winding of variometer 21 is connected to the front winding terminal of winding 24 through a sliding connection and thence to the terminal 15 by the lead 31. Similarly to connector 27, connector 32 connects the terminals of windings 25 and 26 and serves as a support for the brush 33 engaging the slip ring 34 which serves as a flexible driving connection and is connected electrically to the rotor windings of variometers 22 and 23. Connector 32 is connected to the terminal 17 by the lead 35.

The rear winding terminal of winding 26 and the rear winding terminal of the rotor of variometer 23 are connected to the semi-circular contact sector 36 which engages the contact 37 during approximately one-half the rotation of the shaft to which sector 36 is connected. The contact 37 is mounted on the support plate 38 attached to the structure of the variometer 23 and is connected to the radio frequency output terminal 9 by the lead 39 secured to the anti-corona connector 40. The rod 41 merely serves as a stiffener for the support plate 38. The variometers 21, 22, 23 are mounted so that the rotation centers of the variometer rotors lie on a single line and the rotors may be driven to a number of predetermined positions by the motor and preselector assembly 42 driving the rotor of variometer 21 through the flexible driving connection 43.

The structure of the variometer assembly is more clearly seen in the top view of Figure 2 showing the variometers 21, 22, 23 secured in place between the variometer support rods 19 by the screws 44 and the connection of the windings 24 and 25 to the series connector 27 and to the terminal 16 by the connection 30 between connector 27 and the terminal 16. Also shown in this view are the flexible drive coupling 43 connecting the rotor of variometer 21 to the controlled drive shaft of the motor and preselector 42, and the connections between adjacent variometer rotors including the rotor shafts 45, the shaft stub inserts 46 and the flexible drive coupling hubs 47.

In the cross sectional view of the rotor in Figure 3, there is seen the rotor hub 48 pinned to the rotor shaft 45 by the pin 50 and to the rotor coil form 51 by the pin 52. Iron cores 53 are held in place against the rotor hub 48 by the sleeves 54 secured to the rotor shaft 45 by the pins 55 and serve to materially increase the inductance range of the variometer. The shaft stub inserts 46 are forced into the ends of the rotor shaft 45 and may be secured in place by cementing or using some other suitable adhesive. The rotor coil 57 is wound over the outside of the rotor coil form 51 and the two ends of the winding are connected individually to the

two shaft stub inserts in the manner shown, the winding leads being brought through apertures in the rotor shaft 45 and then soldered in place in the central aperture of the shaft stud inserts 46.

The rotors are mechanically and electrically connected to one another by the slip ring assembly of Figures 4 and 5 with the slip ring 29 provided with the mounting ears 53 along the inner periphery to which the spring steel arms 59 are riveted. At their inner end, the arms 59 carry the coupling hubs 47 which are provided with set screws for attaching to the shaft stubs of the shaft stub inserts 46. A slip ring assembly of this type is employed in making the electrical and mechanical connection between the successive variometers 21, 22 of Figure 2. Slip ring 34 is similarly constructed. Equipment of the nature of this antenna tuning unit is called upon to operate over wide ranges of temperature which may cause considerable distortion of the variometer support rod 19. This distortion is of such magnitude as to cause binding of the variometer rotors in their bearings if a solid drive shaft and mounting are employed for the variometer rotors. This defect is overcome by the use of the combined slip ring and flexible drive coupling assembly just described to connect the rotors of the variometers mechanically and electrically so that each variometer rotor shaft rotates freely and independently in its own bearings located in the stationary frame of the variometer.

The disconnect mechanism at the rear end of the rotor shaft of the last variometer 23 is clearly seen in the end view of Figure 6 showing the variometer 23 located between the variometer support rods 19 and the contact sector 36 affixed to and driven by the rotor shaft of variometer 23 and connected to one terminal of the rotor winding and one terminal of the stator winding 26 of this variometer. So long as the arcuately shaped portion of the sector 36 is opposite the contact 37, these two points are connected electrically, but upon rotation of the shaft to place the flat side of the sector 36 opposite the contact 37, the circuit is broken. The relation of sector 36 and contact 37 to each other is such that they are in contact during approximately the 180 degrees of rotation required for the inductance of the variometers to pass from maximum to minimum.

The operation of the antenna unit described in the foregoing figures in its intended position in a radio transmitting system is most readily understood by consultation of the schematic diagram of Figure 7. The variometers 21, 22, 23 have their rotor and stator windings connected in parallel, and the three variometers are then connected in series, with the intermediate connections brought out to the contacts 16 and 17. The ends of the series circuit including the variometers 21, 22, 23 are connected to the contact 15 and to the semicircular contact sector 36 respectively and the number of variometers in the antenna circuit is controlled by the position of the quick detachable connector 14 at the end of the lead 11 extending from the front contact of relay 6. The rear contact of relay 6 is connected to the radio frequency output terminal 9 by the lead 10 and the central movable contact is connected to the radio frequency input terminal 1 through the antenna current indicating ammeter 2. The rotors of the variometers are driven by the control shaft 60 extending from the motor and preselector assembly 42, as is also the semicircular contact sector 36 which engages the fixed

contact 37 connected to the radio frequency output terminal during approximately 180 degrees of shaft rotation in which the inductance of the variometers varies from minimum to maximum.

- 5 In the de-energized position of relay 6, the input terminal 1 is connected directly to the output terminal 9 while in the energized position, the input terminal 1 is connected to the output terminal 9 in series with a number of variometer sections determined by the position of the connector 14 and with the contact sector 36 and contact 37.
- 10 The preselector 42 is provided with a number of notched discs 61, 62, 63, 64, and 65 mounted on the shaft 60 whose individual peripheries are engaged by followers on the switches 66, 67, 68, 69, and 70 which are closed except when the notch in the associated disc lies directly under the follower on the movable switch arm. Switch 20 70 also operates the switch 71 from the disc 65. The fixed contacts of switches 66, 67, 68, 69, and 70 are connected in parallel and to one of the input terminals of the ratchet motor 72 which actuates a pawl driving a ratchet wheel 25 on the shaft 60. The other power input terminal of the ratchet motor 72 is connected to ground and the operating winding is shunted by the spark-suppressing condenser 73. The ungrounded input terminal of the ratchet motor 30 is also connected to the indicator lamp 56 located in the remote channel selector which serves as a reminder when the equipment is changing channels so that the operator will not attempt to transmit during this period. The movable 35 arms on the switches 66, 67, 68, 69, and 70 are individually connected to the fixed contacts on the local antenna tuning selector switch 74 and the remote channel selector switch section 75. The wiper arms on switch 74 and on remote 40 channel selector switch sections 75 and 76 are connected together and to the positive terminal of the direct current source 77 having the negative terminal grounded. The positive terminal of source 77 is also connected to the movable 45 arm of switch 71 whose fixed contact arm is connected to one terminal of the operating winding 7 of the vacuum relay 6. The other terminal of winding 7 is grounded and when switch 71 is closed, the relay 6 is actuated by virtue of the 50 current flowing through the above circuit, connecting the input terminal 1 to the variometers through the lead 11.

- The remote channel selector switch section 76 is utilized to control the channel selector located 55 in the transmitter 78. The radio frequency output terminal 79 of the transmitter 78 is connected to the terminal 1 of the antenna loading unit, and the output energy is fed through a circuit controlled by the position of the remote channel 60 selector switch section 75 to the antenna loading unit output terminal 9 and antenna 80. With the switch sections 75 and 76 in the extreme counterclockwise position, the channel selector 65 of the transmitter 78 may be manually set to any desired channel and the antenna loading controlled by the local antenna loading selector 74 located at the antenna loading unit. In the second position of switch 74, the positive terminal of the source 77 is connected to the ungrounded terminal of the ratchet motor 72 through the switch 66 causing the motor to rotate the control shaft 60 and the attached discs until the notch in the disc 61 lies under the follower attached to the movable arm of the switch 75 66, when the switch opens and interrupts the

power supply to the motor 72 bringing the shaft 60 and the driven variometers to a halt in the desired position as shown in Figure 7. The position of the disc 61 on the shaft 60 is adjustable so that it may be set to bring the variometers to any desired position. As the switch 74 successively connects the ungrounded terminal of the source 77 to different disc operated switches, the variometers are similarly rotated by the control shaft 60 until the notch in the disc actuating the selected switch lies under the follower thereby inserting a number of different predetermined values of inductance between the input and output terminals of the antenna loading unit. So long as the follower controlling switches 70 and 71 do not engage the notch in the control disc 65, switch 71 is closed, energizing relay 6 and connecting the antenna input terminal 1 to the connector 14 so that the selected number of variometer sections is connected between the input and output terminals in series with the contact members 36 and 37 which present a closed connection for all the shaft positions defined by the controlling discs 61, 62, 63, and 64. The position of the notch in the control disc 65 bears such a relation to the contact sector 36 that the flat side of this sector is presented to the contact 37, breaking the connection between them, when this notch is engaged by the follower controlling the switches 70 and 71. Therefore, when the source 77 is connected to the movable contact of switch 70, the ratchet motor 72 drives the control shaft 60 to a position where the follower of switches 70 and 71 engages the notch of control disc 65, opening the power supply circuit to the motor 72 and to the operating winding 7 of the relay 6 so that the input terminal 1 is connected directly to the output terminal 9 through the central movable and the fixed rear contact of relay 6. At the same time, the positioning of the shaft 60 disengages the contact 37 from the sector 36, disconnecting the variometers from the output terminal 9. The corresponding position of the selector switch 74 is termed the "HF" or high frequency position, as it is used when the frequency to be radiated is sufficiently high to eliminate the need for antenna loading.

The disconnection of the variometers from the antenna circuit, except when they are required for optimum transmitter loading, has been found to produce a large increase in the radiated energy in those portions of the spectrum in which the loading may be deleterious. When even one terminal of the variometer circuit is permanently connected to the antenna circuit, there are many frequencies in which the major portion of the transmitter output power is dissipated in parasitic resonances within the variometer structure. Because of the high voltages found in this service during low frequency transmission, the in-line arrangement of the variometers imparts the best performance characteristics due to the lower potential gradients encountered.

When simultaneous remote control of both the transmitter 78 and the antenna tuning unit is desired, the local antenna tuning selector 74 is placed in the extreme counterclockwise position and the remote channel selector incorporating the switch sections 75 and 76 is utilized. Switch section 76 selects eight different preselected transmitter channel frequencies produced by the transmitter 78, four of which must lie at such a part of the frequency spectrum that antenna loading is not required when the antenna loading unit, which has been described, is used. Channel

75 selector switch section 75, whose wiper arm is mechanically coupled to the wiper arm of section 76 by the mechanical connection 81, simultaneously energizes the preselector switch which will index the control shaft carrying the variometers 21, 22, and 23 in the antenna loading unit to the position providing the proper antenna loading. In the four extreme clockwise positions of the switch arm in section 75, the high frequency switch 79 is energized, indexing the control shaft to a position disconnecting the variometers from the antenna circuit by the action of sector 36, contact 37, and the operation of the relay 6. The connections of the transmitter channel selector to the switch section 76 are such that the highest frequency operating channels are selected in the four extreme clockwise positions of this selector switch.

The set up procedure followed after the installation of this equipment in an aircraft is as follows: The transmitter is set in operation with the remote channel selector in the desired position and adjusted to provide the lowest desired output frequency, the screw securing the control discs to the shaft 60 is loosened, control shaft 60 operating the variometer rotors is rotated to the setting giving the maximum indication on the radio frequency current meter 2, and with shaft 60 in this position, the control disc associated with the control switch now energized by the channel selector switch section 75 is rotated so that the notch engages the switch follower. This process is repeated for each of the remaining three low frequency channels, but on the high frequency channels only the transmitter need be adjusted, as switch 78 engaging the control disc 65 is energized on all the high frequency channels. On the high frequency channels, therefore, the control shaft 60 is rotated by the motor 72 to a position disengaging sector 36 and contact 37 and disconnecting terminal 9 from the variometers. After all the above adjustments have been completed, the screw securing the control discs to the shaft 60 is retightened and, henceforth, setting the channel selector to any one of the low frequency channels simultaneously places the transmitter in operation on the desired channel and loads or tunes the antenna circuit to provide maximum radiation. When making the initial adjustment on the lowest frequency channel, the connector 14 is positioned to resonate the antenna circuit at the selected frequency with the smallest number of variometers in the circuit. When a very small antenna is used, it is generally necessary to place the connector 14 on the terminal 15, thereby inserting all three variometers in the antenna circuit on the low frequency channels, while the use of a large antenna enables the attachment of the connector 14 to the terminal 17 eliminating all but variometer 23 from the circuit.

It will be noted in the drawings that all parts operating at high radio frequency potentials are provided with anti-corona terminals or connectors having rounded surfaces. The following radii of curvature have been found satisfactory: For terminals 9, 12, and 13, one-half inch; for terminal 40 and brush 37, three-eighths inch; for sector 36, one-fourth inch; and for the corona shield 18, seven-thirty-seconds of an inch.

In evaluating the performance of antenna loading units, it is to be remembered that the voltage developed at the antenna terminals is inversely proportional to the antenna reactance; thus, halving the antenna capacity doubles the antenna

potentials existing within the loading unit for the same radiated power. The factor determining the minimum size of antenna which may be successfully loaded, exclusive of inductance limitations, is the potential at which arc-over occurs within the antenna loading unit, the greater this potential, the greater the range of antennas which may be accommodated. The following characteristics serve to indicate the improvement in performance and reduction in size and weight which have been realized by the use of the antenna loading unit design described above. The antenna capacity indicated is the minimum which may be resonated at 300 Kc and 31,000 ft. altitude.

	Switched coil design	In line vari- ometer design
Minimum antenna capacity	250 mmfd.	125 mmfd.
Space occupied	3,415 cu. in.	1,552 cu. in.
Percent reduction in volume		54.4.
Weight	28 lbs.	16 lbs., 7 oz.
Percent reduction in weight		41.2.

An inspection of the above table indicates that the range of antennas which may be accommodated has been doubled while at the same time halving the volume occupied and almost halving the weight of the unit.

It will be obvious that many changes and modifications may be made in the invention without departing from the spirit thereof as expressed in the foregoing description and in the appended claims:

1. In radio apparatus, an antenna loading unit, comprising a control shaft, motor and preselector means for driving said control shaft to a plurality of predetermined positions, a radio frequency input terminal, a radio frequency output terminal, a plurality of variometers having a rotatable winding connected in parallel with a fixed winding, means for mounting said variometers in spaced relation with the axes of rotation of said rotatable windings collinearly located, means electrically connecting said variometers in series, a driving connection between said control shaft and said variometers, means for connecting said radio frequency output terminal with an end terminal of the series circuit including said variometers, and means for selectively connecting said radio frequency input terminal with said series connecting means.

2. In radio apparatus, an antenna loading unit comprising, a control shaft, motor and preselector means for driving said control shaft to a plurality of predetermined positions, a radio frequency input terminal, a radio frequency output terminal, a plurality of variometers each having a rotatable winding mounted on an insulating rotor and electrically connected to a fixed winding, insulating means for mounting said variometers in spaced relation with the axes of rotation of said rotatable windings collinearly located, means electrically connecting said variometers in series, a flexible drive coupling connecting said control shaft and the rotor of one of said variometers, flexible drive couplings connecting the rotors of the remainder of said variometer rotors with each other and with the rotor of the driven variometer, means for connecting said radio frequency output terminal with an end terminal of the series circuit including said variometers, and means for selectively connecting said radio frequency input terminal with said series connecting means.

3. In an antenna loading unit, a radio fre-

quency input terminal, a radio frequency output terminal, a variable impedance element controlled by a continuously rotatable shaft and controllable between the maximum and minimum limits of impedance upon rotation of said shaft through a control rotation sector of less than 360 degrees, disconnect means operated by the rotation of said control shaft connecting one terminal of said impedance to said output terminal for control shaft positions lying within said control sector and disconnecting said terminal of said impedance from said output terminal for control shaft positions lying without said control sector, and switching means connecting said radio frequency input terminal to the other terminal of said impedance when the circuit through said shaft controlled disconnect device is closed and connecting said radio frequency input terminal to said radio frequency output terminal when the circuit through said shaft controlled disconnect device is open.

4. In an antenna loading unit, a radio frequency input terminal, a radio frequency output terminal, a variable impedance controlled by a continuously rotatable shaft and controllable between the maximum and minimum limits of impedance upon rotation of said shaft through a control rotation sector of less than 360 degrees, a circular conducting sector actuated by said control shaft and subtending an angle at least equal to said control sector, means connecting said circular sector to one terminal of said impedance element, a contact member intermittently engaging said circular sector, means connecting said contact member to said radio frequency output terminal, and means connecting said radio frequency input terminal to the other terminal of said impedance element and to said radio frequency output terminal.

5. In an antenna loading unit, a radio frequency input terminal, a radio frequency output terminal, a variable impedance controlled by a continuously rotatable shaft and controllable between the maximum and minimum limits of impedance upon rotation of said shaft through a control rotation sector of less than 360 degrees, a circular conducting sector connected to said impedance actuated by said control shaft and subtending an angle at least equal to said control sector, motor and preselector means for driving said control shaft to a plurality of predetermined positions, a contact member intermittently engaging said circular sector, means connecting said contact member to said radio frequency output terminal, and switching means connecting said radio frequency input terminal to the other terminal of said impedance element when said contact member is in engagement with said circular sector and connecting said radio frequency input terminal to said radio frequency output terminal when said contact member is disengaged from said circular sector.

6. In an antenna loading unit, a radio frequency input terminal, a radio frequency output terminal, a variable impedance controlled by a continuously rotatable shaft and controllable between the maximum and minimum limits of impedance upon rotation of said shaft through a control rotation sector of less than 360 degrees, a circular conducting sector actuated by said control shaft and subtending an angle at least equal to said control sector, means connecting said sector to one terminal of said impedance, a contact member intermittently engaging said circular sector, motor and preselector means for driving said control shaft to a plu-

rality of predetermined positions, one of said positions disengaging said contact member from said circular sector, means connecting said contact member and said radio frequency output terminal, and switching means for selectively connecting said radio frequency input terminal to the other terminal of said impedance element and to said radio frequency output terminal.

7. In an antenna loading unit, a radio frequency input terminal, a radio frequency output terminal, a control shaft, a plurality of variometers driven by said control shaft, means electrically connecting said variometers in series, a substantially semicircular conducting sector rotatably driven by said control shaft, means connecting said conducting sector to one terminal of the series circuit including said variometers, a contact member intermittently engaging said conducting sector, means connecting said contact member to said radio frequency output terminal, and means for selectively connecting said radio frequency input terminal to the windings of said variometers and to said radio frequency output terminal.

8. In an antenna loading unit, a radio frequency input terminal, a radio frequency output terminal, a control shaft, a plurality of variometers driven by said control shaft, means electrically connecting said variometers in series, a substantially semicircular conducting sector rotatably driven by said control shaft, means connecting said conducting sector to one terminal of the series circuit including said variometers, a contact member intermittently engaging said conducting sector, means connecting said contact member to said radio frequency output terminal, motor and preselector means for driving said control shaft to a plurality of predetermined positions, one of said positions disengaging said contact member from said sector, and means for selectively connecting said radio frequency input terminal to the windings of said variometers and to said radio frequency output terminal.

9. In antenna loading unit, a radio frequency input terminal, a radio frequency output terminal, a control shaft, a plurality of variometers driven by said control shaft, means electrically connecting said variometers in series, a substantially semicircular conducting sector rotatably driven by said control shaft, means connecting said conducting sector to one terminal of the series circuit including said variometers, a contact member intermittently engaging said conducting sector, means connecting said contact member to said radio frequency output terminal, motor and preselector means for driving said control shaft to a plurality of predetermined positions, one of said positions disengaging said contact member from said sector, and means for selectively connecting said radio frequency input terminal to the windings of said variometers during the engagement of said sector by said contact member and connecting said radio frequency input terminal to said radio frequency output terminal when said contact member is disengaged from said sector.

10. In radio apparatus, an antenna loading unit comprising a control shaft, motor and preselector means for driving said control shaft to a plurality of predetermined positions, a radio frequency input terminal, a radio frequency output terminal, a plurality of variometers driven by said control shaft, means connecting said variometers in series, relay means alternatively feeding energy from said radio frequency input

terminal directly to said radio frequency output terminal and to said output terminal through at least a portion of said plurality of variometers, and means for controlling the number of variometers traversed by said energy.

11. In radio apparatus, an antenna loading unit comprising a control shaft, motor and preselector means for driving said control shaft to a plurality of predetermined positions, a radio frequency input terminal, a radio frequency output terminal, a plurality of variometers each having a rotatable winding whose terminals are directly electrically connected to the terminals of the fixed winding most closely coupled thereto, means for mounting said variometers in spaced relation with the axes of rotation of said rotatable windings collinearly located, means electrically connecting said variometers in series, a driving connection between said control shaft and said variometers, means alternatively feeding energy from said input terminal directly to said output terminal and to said output terminal through at least a portion of said plurality of variometers, and means for controlling the number of variometers traversed by said energy.

12. In radio apparatus, an antenna loading unit comprising a control shaft, motor and preselector means for driving said control shaft to a plurality of predetermined positions, a radio frequency input terminal, a radio frequency output terminal, a plurality of variometers each having a rotatable winding electrically connected to a fixed winding, means for mounting said variometers in spaced relation with the axes of rotation of said rotatable windings collinearly located, means electrically connecting said variometers in series, a driving connection between said control shaft and said variometers, disengageable connecting means between one of said radio frequency terminals and an end terminal of the series circuit including said variometers, and relay means alternatively connecting said radio frequency terminals together when said disengageable connector is disengaged and connecting the other radio frequency terminal to another point on the series circuit including said variometers when said disengageable connector is engaged.

13. In an antenna loading unit, a radio frequency input terminal, a radio frequency output terminal, a variable reactor having a plurality of terminals controlled by a rotatable shaft, and controllable between predetermined limits of reactance upon rotation of said shaft through a control rotation sector of less than 360 degrees, means connecting one terminal of said reactor to one of said radio frequency terminals when said control shaft is positioned within said control sector and disconnecting said reactor terminal from said one terminal when said control shaft is positioned without said control sector, and means for connecting the other of said radio frequency terminals alternatively to another terminal of said reactor when said control shaft is positioned within said control sector and to said one radio frequency terminal when said control shaft is positioned without said control sector.

14. In an antenna loading unit, a first terminal, a second terminal, a variable impedance element having a plurality of terminals controlled by a rotatable shaft and controllable between predetermined limits of impedance upon rotation of said shaft through a control sector of

13

less than 360 degrees, means connecting one terminal of said impedance element to said first terminal when said shaft is positioned within said control sector and disconnecting said one terminal of said impedance from said first terminal when said shaft is positioned without said control sector, and means alternatively connect-

14

ing said second terminal alternatively to another terminal of said impedance element when said shaft is positioned within said control sector and to said first terminal when said shaft is positioned without said control sector.

JOHN W. HAMMOND.
